DESIGN FOR A COMBINED MAP AND CLOCK FACE

Andre Tellier, New York, N. Y.

Application April 6, 1946, Serial No. 128,331

Term of patent 14 years

(Cl. D42—7)

To all whom it may concern:

Be it known that I, Andre Tellier, a citizen of the United States of America, residing at New York city, New York County, and State of New York, have invented a new, original, and ornamental Design for a Combined Map and Clock Face, of which the following is a specification, reference being had to the accompanying drawing, forming part thereof.

Fig. 1 is a plan view of a combined map and clock face showing my new design, the back of the same being plain.

Fig. 2 is an edge view thereof.

I claim:

The ornamental design for a combined map and clock face, substantially as shown and described.

ANDRE TELLIER.
